UNITED STATES PATENT OFFICE.

HERMAN F. GERHARD, OF UNIVERSITY, MISSOURI.

COVERED PULLEY.

1,309,284.

Specification of Letters Patent. Patented July 8, 1919.

Application filed August 2, 1918. Serial No. 248,042.

To all whom it may concern:

Be it known that I, HERMAN F. GERHARD, a citizen of the United States, residing at 6665 Kingsbury Blvd., University, and State 5 of Missouri, have invented new and useful Improvements in Covered Pulleys, of which the following is a specification.

This invention relates to covered pulleys and method of covering the same, the main 10 object of the invention being to provide a pulley with a covering of material that will tend to prevent slippage of the belt, and which covering will be securely held upon the surface of the pulley.

15 The invention may be applied indifferently to wooden or metal pulleys; but the advantages thereof are more apparent in connection with metal pulleys, which have always proven difficult to provide with covers that will remain securely fixed to the surface of the pulley for any considerable time.

According to my invention I use a covering 20 of open work material, such as may be produced by a fabric made from woven cords presenting interstices between them. Such material is illustrated by a well known type of press cloth, which, as a matter of fact, I find very advantageous to use. I 25 may, however, take other material, such as leather, canvas, or the like, and provide the same with interstices by punching or cutting small openings therein. The covering is secured to the pulley through the medium 30 of a suitable cement, which is applied in sufficient quantity not only to cover the surface of the pulley, but to project into and fill the interstices of the fabric or other covering. After the cement hardens, there will 35 be a large number of projections on the surface of the pulley, formed by the hardened cement which has filled the interstices in the covering, and these projections, extending entirely around the surface of the pulley, 40 and extending through said interstices and engaging the walls thereof, tend to, and do, prevent slippage of the covering about the pulley, so that a pulley so covered may be used for a great period of time, as compared 45 with the life of covers as at present applied, without it being necessary to renew the covering.

The cement I employ is one which will

harden by evaporation, or oxidation, and any cement that will bind the covering to the 55 surface of the pulley, that is to say, that will adhere to metal, or wood and fabric, leather, or the like, and which possesses the property of hardening, may be employed.

In the accompanying drawing:

Figure 1 is a plan view of a portion of a pulley with the covering applied thereto according to my invention;

Fig. 2 is a fragmental side elevation showing the pulley as it would appear with the 65 covering removed, to illustrate the series of projections formed by the cement filling the interstices of the covering;

Fig. 3 is a view of a section of open work fabric, such as I might use; and,

Fig. 4 is a view showing a section of any suitable covering material having interstices punched or cut therein.

In proceeding according to my invention, I first coat the surface of the pulley with the 75 cement. After this first coating of cement has been allowed to harden to a greater or less degree, I apply a second coating of cement. I then place the covering about the pulley and then coat the covering with the 80 cement, making sure that all of the interstices are filled with the cement. A hand roller may be used to firmly press the covering about the pulley and to insure that the cement is forced into and fills the interstices of the covering. The cement is then 85 allowed to harden, and the pulley will have the appearance shown in Fig. 1.

The numeral 1 in the drawing indicates the pulley, 2 the covering, 3 the interstices 90 in the latter, 4 the layer of cement securing the cover to the pulley and 5 the projections formed by the cement filling the said interstices.

In Fig. 2 the numeral 6 indicates a portion 95 of any suitable covering material such as canvas or leather, having openings 7 punched or cut therein.

I claim:

1. A pulley having a cover of open work 100 material thereon affording free openings of considerable area and secured to the pulley by means of a binder having a series of fixed projections extending into the interstices of said material, the relatively rough surface 105 of the cover being exposed to exert its grip-

ping or tractive effect on the inner surface of a belt applied thereto.

2. A pulley having a cover thereon affording free openings of considerable area, said cover being secured to the pulley by means of an interposed coating of hardened cement which has been caused to fill the openings

of said cover thereby presenting numerous fixed projections integral with the coating of cement and engaging the walls of said 10 openings.

In testimony whereof I have hereunto set my hand.

HERMAN F. GERHARD.
